UNITED STATES PATENT OFFICE.

CHARLES D. JOHNSON AND FREDERICK W. LODDING, OF WORCESTER, MASSACHUSETTS.

CONTINUOUS-WIRE-DRAWING MACHINE.

1,322,904.

Specification of Letters Patent. Patented Nov. 25, 1919.

Application filed August 16, 1918. Serial No. 250,228.

To all whom it may concern:

Be it known that we, CHARLES D. JOHNSON, a citizen of the United States, and FREDERICK W. LODDING, a subject of the 5 King of Norway, both residing at Worcester, in the county of Worcester and State of Massachusetts, have invented a new and useful Continuous-Wire-Drawing Machine, of which the following is a specification.

10 This invention relates to a wire drawing machine of the continuous type, and the principal objects thereof are to so arrange the parts of the machine as to concentrate them into a smaller space than has been possible heretofore; to provide a construction 15 in which the wire can be drawn through a part only of the dies when desired, in a most convenient manner without necessitating any changes in the machine or in its 20 speed of operation, and at the same time permitting of the throwing out of gear of the parts of the machine not required without in any way interfering with the reduction of the diameter of the wire; and to provide 25 for changing the speed of the winding drum in a simple manner without interfering with the rest of the machine.

Reference is to be had to the accompanying drawings in which—

30 Figure 1 is a plan of a preferred embodiment of this invention;

Fig. 2 is a front elevation;

Fig. 3 is a sectional view on the line 3—3 of Fig. 2 showing the driving mechanism 35 in plan, and

Fig. 4 is a sectional view on the line 4—4 of Fig. 1.

As ordinarily constructed wire drawing machines of the continuous type comprise 40 a series of dies arranged in alignment and a series of forwarding rolls or cylinders around which the wire passes arranged one between each two dies as is well understood. A machine of this kind takes up 45 considerable room on account of its length, and by our new arrangement we succeed in reducing the length very materially and increase the width only to a comparatively slight degree. It may be said that for a machine of the particular size shown the length 50 is reduced to a third and the width only about doubled thus materially economizing in space. On the old type of machines also when all the dies are to be used no special 55 difficulty is encountered, but when only a

part of them are to be used the wire has to be run into the machine at some point beyond the usual first roll and there is no convenient way of taking the wire off from any intermediate roll so that the dies have to be 60 replaced and the entire operation is awkward and unmechanical. We find in practice also that it is impossible with the old machines to get exactly the speed required for the reason that there is no way to secure 65 a fine adjustment of the speed. This often shows up in the machine by a violent chattering of the wire as it passes through the dies. According to our invention this chattering is substantially eliminated and the 70 wire is passed through the dies in a smooth, uniform and accurate condition by providing a fine easily regulatable adjustment for the speed of the winding drum without 75 altering the speed of the forwarding rolls. 75

Referring now to the drawings it will be seen that the machine is shown as comprising a cast metal base 10 on which is a cast iron tank 11 in which are located dies 12 and 13, the numeral 12 indicating the series 80 of dies around the tank for receiving the wire from and passing it to the several forwarding rolls, and the numeral 13 the finishing die which in the normal machine is always located in the same place, but in this 85 machine may be placed at any desired point in the tank around the center thereof.

We have shown the machine as driven 90 from tight and loose pulleys 14 on a driving shaft 15. This shaft is provided with three bevel gears 16 operating three bevel gears 17 on the bottoms of three shafts 18. The shaft 15 is also shown as provided with a spur gear 19 which drives a series of spur gears 20, all shown as of equal pitch diameter. 95 Two of these spur gears 20 drive parallel shafts 21 and 22. The shaft 22 drives three upright shafts 18 by the same means as the shaft 15, and the shaft 21 drives two of them, so that there are altogether eight of 100 these upright shafts 18.

Each of these shafts carries a forwarding roll 25 at the top located in the tank, the shafts passing up through babbitted bearings 26 in the bottom of the tank. It will be 105 understood from consideration of the sizes of the bevel gears that the various shafts 18 run at different speeds. The first drum #1 is the slowest one, and the others Nos. 2, 3, 4, 5, 6, 7 and 8 are speeded up to higher 110

speeds in the necessary proportion as is the case with the usual continuous drawing mills. But in this case there is a central shaft 30 mounted in bearings on a frame 31 which is part of the main frame 10 and also in a babbitted bearing in the bottom of the tank 11. This carries a winding drum 32 rotating on an elevated center 33 of the tank. This winding drum is of the usual character, and need not be described in detail but it constitutes a center about which the forwarding drums are located in the form shown. The essential point however is that they are not located in alinement with each other or with the winding drum but are at nearly equal distances from the winding drum and grouped around it. As shown they form the sides of a hollow square.

The shaft at the bottom is provided with a spring 34 on the bottom of the frame 31 pressing on a disk 35 which is keyed to the shaft. On the shaft 21 is a driving friction disk 36 slidingly keyed to it and provided with means not shown for sliding it along the shaft. The spring 34 holds the disk down in contact with it. It will be seen therefore that the speed of the shaft 30 can be regulated within fine limits and in a very simple manner.

The location of the several forwarding drums 1, 2, 3, 4, 5, 6, 7 and 8 around the winding drum 32 is an important feature of this invention. When in ordinary operation the wire is to be drawn through nine dies 12 and 13 all the rolls are employed and the wire passes from the reel 39 to the roll No. 1 through a die 12 and then in turn around all the rolls, each of which draws the wire through a die. From the roll 8 the wire passes to the winding drum 32. We have shown the wire, however, passing from the roll 6 directly to the winding drum through the finishing die 13 in order to illustrate how easy it is to drop out two of the dies and forwarding rolls without interfering with the operation of the machine in any way. It is to be understood, of course, that the finishing die 13 is placed around the drum in any desired position to permit of securing this result. The construction by which this is provided for consists simply in a series of slots 40 in a sta-

tionary part of the tank in any one of which the die 13 can be fastened by a bolt.

Although we have illustrated and described only a single form of the invention we are aware of the fact that many modifications can be made therein by any person skilled in the art without departing from the scope of the invention as expressed in the claims. Therefore we do not wish to be limited to all the details of construction herein shown and described, but what we do claim is:—

1. In a wire drawing machine, the combination with a winding drum, of a set of forwarding rolls, all of the same size, and dies arranged on different sides of the winding drum in the form of a square with three rolls on each side, a finishing die adapted to be placed between the winding drum and different ones of the forwarding rolls, gearing positively connecting said rolls together to rotate at different speeds, means for driving the winding drum from said gearing, and means for minutely varying the speed of the winding drum independently of the speed of the forwarding rolls.

2. In a wire drawing machine, the combination with a winding drum, of a set of forwarding rolls all of the same size, and dies all arranged near the winding drum, and means whereby a finishing die can be placed between the winding drum and any one of the forwarding rolls, so that the wire may be passed from any of the rolls directly to the winding drum and finished without interfering with the other rolls or changing the way of entering the wire into the machine.

3. In a wire drawing machine, the combination with a winding drum, of a set of forwarding rolls and dies arranged around the winding drum, means whereby a finishing die can be placed between the winding drum and any one of the forwarding rolls, so that the wire may be passed from any of the rolls directly to the winding drum and finished thereby, and means for varying the speed of the winding drum.

In testimony whereof we have hereunto affixed our signatures.

CHARLES D. JOHNSON.
FREDERICK W. LODDING.
